UNITED STATES PATENT OFFICE.

JULIAN MACARTNEY OGILVIE, OF LONDON, ENGLAND.

CINEMATOGRAPHIC SCREEN.

1,426,317.

Specification of Letters Patent. Patented Aug. 15, 1922.

Application filed August 22, 1921. Serial No. 494,358.

To all whom it may concern:

Be it known that I, JULIAN MACARTNEY OGILVIE, a subject of the King of England, residing at 68 Warwick Gardens, 5 Earls Court, London, S. W., England, have invented certain new and useful Improvements in Cinematographic Screens (for which I have filed applications in England Aug. 16, 1920, Sept. 9, 1920, and May 17, 10 1921), of which the following is a specification.

This invention relates to screens for use in connection with cinematograph lanterns and like projection apparatus, of the kind 15 having a metallic surface formed of powdered aluminium silver, bronze, or the like.

The object of the invention is to make such screens capable of producing a colour effect instead of the usual black and white 20 effect produced by the present screens of this type. Another object of the invention is to reduce as far as possible the shadow effect which is rather pronounced with metallic or metallized screens when viewed 25 from acute angles and to obtain an even diffusion of light at all angles of observation.

As far as the colour effect is concerned the main feature of the invention consists in 30 the use of a coloured background on to which the metallic powder is dusted or otherwise applied. Whilst any colours except black and white may be used, the colours preferably used are orange, or red, as being 35 most suitable for general use. Green and blue backgrounds may be suitable for reproduction of wooded and like scenery and of sea-scapes.

Whilst the metallized surface of the screen 40 has generally the effect of reflecting the light and of producing a very clear reproduction of fine detail, the coloured background has the effect of giving a certain tone to the picture.

45 For reducing the shadow effect and for matting the brilliant metallic surface barium sulphate is used as a final coating, which is spread on to or otherwise applied to the metallic coating. The barium sulphate may also be mixed with the metallic powder.

The coloured background for the metallic surface may be produced in any suitable manner, but it is preferred to prepare this 55 background in such a manner as to enable

the metallic surface to be formed thereon in the usual manner.

In the accompanying drawing, Figure 1 is a view of a portion of a screen with parts of the coatings broken away. 60

Figure 2 is a sectional view therethrough.

A screen embodying the features of the invention may be prepared in the following manner. A canvas or cotton fabric 1 in one seamless sheet is prepared in the usual 65 way for painting. One or more coats of paint containing each white lead, red lead (or orange powder or other colouring matter), genuine linseed oil and liquid driers, are then applied either by means of a brush 70 or of a hand-spraying machine. If hand-painting is used the surface should be carefully stippled. A final coat is then applied which contains, in addition to the above mentioned ingredients, heavy stand 75 oil. A metallic powder 2, for instance aluminium powder, is then thrown by hand upon the final coating, which should be in a suitable condition, i. e., nearly dry, but should have sufficient tackiness to hold the 80 powder. The metallic powder is gently brushed all over the surface and is finally, after a suitable interval, brushed off. The powder may, of course, be applied in any 85 other suitable manner, for instance, it may be sprayed on. The sheet is then sprayed one or more times with a mixture 3 of highly refined barium sulphate and glue dissolved in water. Instead of spraying the barium sulphate on to the aluminium, the 90 barium sulphate may be mixed with the aluminium.

The combination of a coloured background with a metallic surface consisting of powdered metal is the main feature of 95 the invention, the object of the coloured background being to soften the hard effect produced by the metallic surface and to give a definite tone to the picture.

I claim—

1. A cinematographic screen comprising a colored background, a metallic surface of powdered aluminum, and an outer coating of barium sulphate.

2. A cinematographic screen comprising 105 a red background, a metallic surface of powdered aluminum, and an outer coating of barium sulphate.

3. A cinematographic screen comprising 110 a sheet of fabric, a plurality of coats of

red paint, a metallic surface, and an outer mat coating of barium sulphate.

4. A cinematographic screen comprising a coat of white lead, red lead, genuine linseed oil and liquid driers; a coat containing (in addition to the above ingredients) heavy stand oil; a metallic powder surface thrown upon the aforesaid coating; and a coating of barium sulphate sprayed upon

the metallic surface, substantially as described. 10

In testimony whereof he has hereunto set his hand in the presence of two witnesses.

JULIAN MACARTNEY OGILVIE.
